UNITED STATES PATENT OFFICE.

JULIUS FEKETE, OF NEW YORK, N. Y.

COMBINATION FOLDING COT AND STRETCHER.

1,144,760.

Specification of Letters Patent. Patented June 29, 1915.

Application filed March 30, 1915. Serial No. 18,020.

To all whom it may concern:

Be it known that I, JULIUS FEKETE, a citizen of the United States, and a resident of the city of New York, in the county of New York and State of New York, have invented certain new and useful Improvements in Combination Folding Cots and Stretchers, of which the following is a specification.

10 The present invention relates to folding cots, and has for one of its objects to provide a construction which is light, durable, simple, inexpensive to manufacture, and which can be readily folded so that it will 15 occupy a small space.

Another object of the invention is to produce means, whereby the cot is held in its extended position against accidental operation, thereby making the structure 20 safe and also reliable in operation.

A further object of the invention is to construct a folding cot, specially adapted for military purposes in that it can be converted conveniently into a stretcher for carrying the bodies of persons, as when 25 wounded or dead.

With these and other objects in view, which will more fully appear as the nature of the invention is better understood, the 30 same consists in the combination, arrangement and construction of parts hereinafter fully described, pointed out in the appended claims and illustrated in the accompanying drawings, it being understood that 35 many changes may be made in the size and proportion of the several parts and details of construction within the scope of the appended claims without departing from the spirit or sacrificing any of the advantages 40 of the invention.

One of the many possible embodiments of the invention is illustrated in the accompanying drawings, in which:—

Figure 1 is a perspective view of a cot 45 constructed in accordance with the present invention in its extended position; Fig. 2 is a perspective view of the same converted into a stretcher; Fig. 3 is an end elevation of the cot in its extended position; Fig. 4 is a plan view of the cot, partly folded; Fig. 5 is a side elevation of the cot entirely folded; Fig. 6 is an end view of the cot in its entirely folded position; Fig. 7 is a section taken on line 7—7 of Fig. 3 50 on a larger scale; Fig. 8 is a bottom plan view of the detail shown in Fig. 7; Fig. 9

is a bottom plan view of the detail shown in Fig. 7 with the foot folded; Fig. 10 is a section taken on line 10—10 of Fig. 9; Fig. 11 is a front elevation of a detail of a hinge connecting the side rail sections of the cot; Fig. 12 is a section taken on line 12—12 of Fig. 11; and Fig. 13 is a perspective view of a portion of one of the transverse rail sections of the cot.

In the drawings, the numeral 20 indicates the top frame of the cot. This frame comprises an oblong structure formed of side rails 21, which are connected by transverse rails 22. Each side rail comprises two sections, denoted by the numerals 23 and 24, each of which is subdivided. More particularly, each of the sections 23 comprises an outer portion 25 and an inner portion 26, and in a similar manner consists each section 24 of an outer portion 27 and an inner portion 28. The portions of each section 23 are hinged together at 29, and the portions of each section 24 at 30. The inner portions of the side rail sections are hinged together at 31. For this purpose the said inner portions are enlarged into circular form, as shown at 32, through the said enlargements passing centrally horizontal pivot pins 33, for instance in the form of 35 screws. These pivot pins are disposed a substantial distance below the lower faces of the side rails, to permit the said side rails to be folded compactly in a manner 40 hereinafter to be described.

The transverse rails 22 are each made of two sections, denoted by the numerals 34. These sections are hinged at their outer ends to the inner faces of the respective outer portions of the side rail sections, the 45 hinges being denoted by the numerals 35. The pintles 36 of these hinges are disposed vertically, and their leaves are attached to the side rails and the transverse rails in such a manner that the latter are adapted 50 to be folded on the inner faces of the said side rails, more particularly they fold outward so that the free ends of the sections of the transverse rails, when folded, are flush with the outer ends of the outer portions of the side rail sections of the cot. One of each pair of transverse rail sections 55 is provided with a dove-tail 37, adapted to enter a similarly shaped mortise 38 in the other section of the pair.

To the underface of each section of the transverse rails is secured a leg 39 by a

hinge 40. The pintles 41 of these hinges are disposed horizontally in the planes of the pintles 36 of the hinges 35. The legs are adapted to be folded on the underfaces of 5 the corresponding sections of the transverse rails, but, when in their extended positions, the outer portions of the side rail sections rest thereon. To maintain the legs in their extended positions there is associated with 10 each of the same a stop 42. These stops are substantially U-shaped in cross section, and carried by the transverse rails. Their flanges 43 abut against the underfaces of the transverse rail sections, and are shiftable 15 thereon toward the transverse center line of the cot. For this purpose the said flanges are provided with slots 44, through which extend studs 45, that are screwed into the transverse rail sections. The lower flanges 20 46 of the stops are considerably shorter than their upper flanges 43, and the heights of their bases 47 are such that the said stops accommodate the legs when the latter are folded, as clearly shown in Fig. 10 of the 25 drawings. Latches hold the stops in their proper positions, each latch comprising a lever 48, pivoted at 49 to the corresponding transverse rail section, and being provided with a hook-shaped end 50, adapted to engage 30 a headed stud 51 upon the corresponding stop 42. When the stops are in their inner positions, in which the outer faces of the bases 47 thereof register with the inner faces of the transverse rail sections, their lower 35 flanges 46 abut against the inner faces of the legs 39, thus keeping the latter in their extended positions (Figs. 3 and 7).

With the outer portions 25 of the side rail sections 23 is associated a head-rest, comprising 40 two links 52, fulcrumed at 53 near to the inner ends of the said outer portions. To the other ends of these links are pivoted at 54 braces 55, having notches 56 in their underfaces, in which are adapted to be seated 45 lugs 57, that are carried by the side rails. The bottom 58 of the cot is formed of any suitable flexible material, capable of being rolled, such as for instance canvas, woven wire, etc. This bottom is attached in any 50 suitable manner to the side rail sections 24, and to the inner portions 26 of the side rail sections 23, and also to the links 52 constituting with the braces 55 the head-rest.

The operation of this device is as follows: 55 When the cot is in its extended position (Figs. 1 and 3), the side rail sections thereof are disposed in a horizontal plane, and supported by the vertically extending legs. The sections of the transverse rails are in engagement with each other, whereby the bed bottom fabric is drawn taut. The legs of the cot are prevented from collapsing or folding by the stops above described. The braces 55 of the head-rest are in engagement with the 60 lugs 57, whereby the said head-rest is held

in an inclined position. Inasmuch as the adjacent sections of the side rails are in abutting relation, the said side rails are firmly held in their extended positions.

If it is intended to convert the cot into a 70 stretcher, the levers 48 are disengaged from the stops 42, and the latter moved toward the transverse center line of the cot, whereby the legs can be folded onto the underfaces of the respective sections of the transverse rails. 75 When now the stops are moved back into the positions in which the outer faces of their bases register with the inner faces of the sections of the transverse rails, and the levers 48 engaged with the headed studs 51 on 80 the said stops, the said legs will be held in abutment with the said transverse rails, the lower flanges 46 of the said stops keeping the same in such positions. The head-rest may be brought into the plane of the side rails, if 85 necessary, (Fig. 2), or it may be kept in its extended position. Inasmuch as the bed bottom fabric extends from transverse rail to transverse rail, the portions of the side rails beyond the fabric act as handles, by which 90 the stretcher can be grasped in transporting the wounded or dead.

When the cot is to be folded for transporting or storage, it is first converted into a stretcher. The transverse rail sections are 95 then disengaged from each other, and folded outwardly against the inner faces of the side rails. The outer portions of the side rail sections are then folded back onto the inner portions thereof, after which the side rails 100 are swung around the pivot pins 33 until the outer portions thereof abut against each other. The two side rails, so folded, are then placed one on top of the other and the bed bottom fabric wound around the same. 105 In Fig. 6 of the drawings the bed bottom fabric has been shown in its open position, in order to more clearly show the positions of the parts in their folded relation. The pivot pins 33 are disposed a substantial distance below the side rail sections and the circular enlargements 32 are provided in order to afford ample space for the outer portions of the side rail sections (Fig. 5).

If the device is to be built as a cot only, 115 that is to say if it is not to be converted into a stretcher, those parts of the outer portions of the side rail sections, which are located beyond the bed bottom fabric, are of no use. In such case, the hinges 29 and 30 may be 120 located nearer the hinges 31, with the result that the structure will be considerably shorter when folded.

What I claim is:—

1. A folding cot comprising a pair of side 125 rails, each side rail consisting of two sections pivotally joined at their inner ends, each of said sections having an inner portion and an outer portion also pivotally joined, said outer portions being adapted to 130

be folded upon said inner portions and the latter being adapted to be swung around their pivots into parallel relation to each other, transverse rails connecting the outer 5 portions of said side rail sections, each transverse rail being made of two sections separably joined at their inner ends and hinged at their outer ends to said side rails, whereby said transverse rail sections are adapted to 10 be folded onto said side rails, a bed bottom fabric secured to said side rails, legs hinged to said transverse rail sections and adapted to be folded thereonto, and means upon said transverse rail sections for holding said legs 15 in their extended positions.

2. A folding cot comprising a pair of side rails, each side rail consisting of two sections pivotally joined at their inner ends, each of said sections having an inner portion 20 and an outer portion also pivotally joined, said outer portions being adapted to be folded upon said inner portions and the latter being adapted to be swung around their pivots into parallel relation to each other, transverse rails connecting the outer 25 portions of said side rail sections, each transverse rail being made of two sections separably joined at their inner ends and hinged at their outer ends to said side rails, whereby 30 said transverse rail sections are adapted to be folded onto said side rails, a bed bottom fabric secured to said side rails, legs hinged to said transverse rail sections and adapted to be folded thereonto, and means upon said transverse rail sections for holding said legs 35 in their extended positions.

3. A folding cot comprising a pair of side 40 rails, each side rail consisting of two sections pivotally joined at their inner ends, each of said sections having an inner portion and an outer portion also pivotally joined, said outer portions being adapted to be folded upon said inner portions and the latter being adapted to be swung around their pivots into parallel 45 relation to each other, transverse rails connecting the outer portions of said side rail sections, each transverse rail being made of two sections separably joined at their inner ends and hinged at their outer ends to said side rails, whereby said transverse rail sections are adapted to be folded onto said side rails, a bed bottom fabric secured to said side rails, legs hinged to said transverse rail sections and adapted to be 50 folded thereonto, and means upon said transverse rail sections for holding said legs in their extended positions, said last named means serving also to keep said legs folded upon said transverse rails.

4. A combination folding cot and stretcher said legs abutting in their extended positions against the underfaces of said side rail sections.

4. A combination folding cot and stretcher comprising a pair of side rails, each side rail consisting of two sections pivotally joined at their inner ends, each of said sections having an inner portion and an outer portion also pivotally joined, said outer portions being adapted to be folded upon said inner portions and the latter being adapted to be swung around their pivots into parallel relation to each other, transverse rails connecting the outer portions of said side rail sections, each transverse rail being made of two sections separably joined at their inner ends and hinged at their outer ends to the outer portions of said side rails substantially at the middle of the latter, whereby said transverse rail sections are adapted to be folded onto said side rails, a bed bottom fabric secured to said side rails, legs hinged to said transverse rail sections and adapted to be folded thereonto, and means upon said transverse rail sections for holding said legs in their extended positions.

5. A combination folding cot and stretcher comprising a pair of side rails, each side rail consisting of two sections pivotally joined at their inner ends, each of said sections having an inner portion and an outer portion also pivotally joined, said outer portions being adapted to be folded upon said inner portions and the latter being adapted to be swung around their pivots into parallel relation to each other, transverse rails connecting the outer portions of said side rail sections, each transverse rail being made of two sections separably joined at their inner ends and hinged at their outer ends to the outer portions of said side rails substantially at the middle of the latter, whereby said transverse rail sections are adapted to be folded onto said side rails, a bed bottom fabric secured to said side rails, legs hinged to said transverse rail sections and adapted to be folded thereonto, and means upon said transverse rail sections for holding said legs in their extended positions.

Signed at New York, in the county of New York, and State of New York, this 11th day of March, A. D. 1915.
